(57) **CLAIM**

The ornamental design for a multifunctional probe detachable soil detector, as shown and described.

DESCRIPTION

FIG. 1 is a front perspective view of a multifunctional probe detachable soil detector, showing my new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof;

FIG. 8 is the expanded plan view of its back; and,
FIG. 9 is the expanded plan view of its front.

The broken lines in the drawings illustrate the portions of the multifunctional probe detachable soil detector, which form no part of the claimed design.
